UNITED STATES PATENT OFFICE.

JAMES E. SMITH, OF NEW YORK, N. Y., ASSIGNOR TO ELIAS LIPINER, OF NEW YORK, N. Y.

TAPE-MACHINE.

1,203,547.

Specification of Letters Patent. Patented Oct. 31, 1916.

Application filed February 18, 1915. Serial No. 9,126.

To all whom it may concern:

Be it known that I, JAMES E. SMITH, citizen of the United States, and resident of the borough of Manhattan, city of New York, in the county of New York and State of New York, have invented certain new and useful Improvements in Tape-Machines, of which the following is a specification.

My invention relates to tape machines and 10 in its specific embodiment as disclosed herein is designed more particularly for use on wrapping counters and in shipping departments and provides an inexpensive, compact, practical and substantially made machine for holding, unrolling, printing, moistening and cutting gummed sealing tape. Although the machine of my invention is 15 designed for use as aforesaid, it is to be understood that it can be used in connection 20 with various kinds of gummed seals and adapted to other use wherein it is found applicable.

Further objects of my invention are to provide a tape machine which is simple in 25 its construction and arrangements, strong, durable, efficient and convenient in its use, providing a quick, simple and inexpensive means for sealing or binding packages and bundles and making the handling of sticky 30 tape with the hands unnecessary.

With the foregoing and other general objects in view, further more specific objects of the invention are to provide: a simple and efficient tape holding device, with a simple means for adjusting the tension on a roll 35 of tape, means for threading the tape over a guarded impression roller, means for inking a printing roller by gravity inking rollers, means for feeding the tape over a roller, means for feeding the tape over a 40 movable moistening device, means for automatically moistening the tape and cutting the desired length thereof, and other arrangements of parts more specifically described and illustrated in the accompanying 45 drawings, which show the detailed embodiments of one form of my invention.

To the above and other ends which will hereinafter appear, my invention consists in the features of construction, arrangement of 50 parts and combination of devices to be hereinafter more fully described and particularly set forth in the appended claims.

In the accompanying drawings wherein like reference characters denote corresponding parts throughout the views, Figure 1. is

a side elevation of the machine fully assembled. Fig. 2. is a side elevation partly in section and with the left side of the frame removed, the view illustrating each part in its normal position. Fig. 3. is a vertical 60 transverse sectional view of the machine taken on the line 3—3 of Fig. 1, and looking in the direction of the arrows at said line. Fig. 4. is a fragmentary vertical transverse sectional view showing the moistening tank 65 and the means of holding the tank in place, the section being taken on the line 4—4 of Fig. 2, and looking in the direction of the arrows at said line. Fig. 5. is a view of the character illustrated in Fig. 2, but showing 70 only the removable type wheel and some of the associated parts. Fig. 6. is a fragmentary detail side elevation with fitted cap removed showing the slot for feeding tape over the impression roller and under a guide 75 roller. Fig. 7. is a detail vertical transverse sectional view taken on the line 7—7 of Fig. 2, and looking in the direction of the arrows at said line. Fig. 8. is a detail plan view 80 partly in section of the removable handle of the type wheel.

A suitable main frame in which all parts are mounted is designated as a whole by the reference numbered 9, and comprises two side frames or members 10 and 11, which 85 have radiating flanges or contact devices 18 and 17 respectively on the inner faces thereof. These side frames are fastened together by five screws 12, and are maintained spaced apart by section 40 and 51 which are 90 front and rear parts extending inwardly from the side frames 10 and 11. The various working parts of the machine are supported by the frame as will hereafter more clearly appear. 95

The tape 13, which preferably consists of a strip of paper coated with an adhesive on one side is wound on a wooden spool 14, in the form of a roll 15, which is mounted to revolve on a knurled headed spindle or shaft 16. This shaft 16 is removably fitted through the side frame 10 and screw-threaded into a tapped opening in the side of the frame 11 for the purpose of holding the roll 15, and for springing the side frames 10 and 11 together, and causing the flanges or contact devices 17 and 18 to engage sides of the roll 15 and exert sufficient pressure thereon to prevent the roll from turning too freely and prevent any tendency of the tape from 100 105 110

uncoiling on the roll. It will be understood that the roll 15 may be introduced into position between the side frames through the open space at the top and rear of the machine where an unobstructed space is provided between the side frames. When the roll is properly positioned, the shaft 16 may be inserted in place through the opening in the spool on which the tape is wound. A shaft 20, screw threaded on one end is removably fitted through the side frame 10 and projects through an opening 21, therein, the opposite end portion of the shaft receiving a bearing in a bearing opening in the side frame 11. A removable cap 22 is screw threaded to fit the threaded end of shaft 20, and to support that end of it on the side frame 10 when the cap 22 is seated in place in the bearing opening 21. The opposite end of the shaft 20 is provided with a knurled head 20^a. An impression roller or platen 23 is removably mounted to revolve on the fixedly supported shaft 20 and has guards, flanges or heads 24 to hold tape 13 in perfect alinement when it is threaded under, around and over the impression roller. Grooved bearings 25 are cut forwardly and then downwardly on inner faces of the side frames 10 and 11, the open mouths of the grooves extending to the rear edge of the side frame. A printing roller 26 on which type 31 may be mounted has trunnions or pivots 27, extending from the ends of roller 26. An inspection of Figs. 2 and 5, indicates how the printing roller may be introduced into place or removed from the machine, the pivots 27 sliding along the bearing grooves 25 and into the vertically disposed portion thereof, to allow the printing roller 26 to rest upon impression roller 23, or the type thereon, and to revolve with the impression roller 23. A detachable handle 28 comprised of two resilient arms 29, provided with bearing openings 30 which receive the pivots 27 of the printing roller. The resiliency of the arms enables them to be sprung apart to receive the pivots of the roller or enable the roller to be detached when desired. When the roller is in place the arms 29 bear lightly against the ends of the roller.

The bearing grooves 25 are extended forwardly at 32 to provide supporting bearings which are adapted to receive the pivots 27 and support the printing roller in an elevated position where it is out of contact with the impression roller 23 and the tape which surrounds it. The printing roller is thus maintained when printing is not desired on the tape 13. To retain the printing roller thus elevated in the non-printing position, I have provided a notch 38 in the lower edge of the finger piece of the handle 28. The notch or engaging portion of the handle is adapted to engage the upper edge of the

part 51 of the frame, as shown in dotted line Fig. 3, and to lock the printing roller indefinitely in the dotted line or non-printing position. Weighted inking rollers 34 with shafts 36, are removably mounted and engaged with each other to revolve together in grooved bearings 35 in the frame. The ends of the shafts are received from above in the open mouths of the inclined bearing grooves 35, and the surface of the lower inking roller bears against the type 31 for the purpose of inking the same. The weight of two inking rollers is supported on the printing roller 26 and forces the latter downwardly in its bearing against the face of the tape supported by the impression roller or platen 23, and thus causes an imprint to be produced on the tape as the latter passes through the machine, as will hereinafter more clearly appear.

85 A guide roller 37, for the tape is provided with a shaft 38, received at its ends in bearing openings 41 in the side frames 10 and 11. The surface of the guide roller is preferably roughened, as indicated at 30, to prevent the printed surface of the tape as it passes over the surface of the guide roller from being smeared.

90 A feed roller 42 is provided with a shaft 43 received at its ends in bearing openings in the side frames. One end of the shaft is threaded for coöperation with a knurled finger wheel 44, by which the shaft and the feed roller secured thereto may be turned. An associated feed or pressing roller 45, is provided with a shaft 46, the ends of which extend through, and are seated and guided in, vertically disposed bearing or guide slots 47 in the side frames 10 and 11. Springs 48 are each connected at one end to one of the 95 side frames and its other end to one end of the shaft 46, thus forcing the pressure roller 45 against the feed roller 42, or against the tape which is received between the rollers 42 and 45. By turning the finger wheel 44, the tape will be reeled off the roll 15, and fed from the machine. A ratchet wheel 46 is formed on the hub of the finger wheel 44 for coöperation with a spring pressed pawl 47 pivoted to the outer side of the side frame 10. This pawl and ratchet wheel insure the turning of the feed roller 42, and pressure roller 45 in but one direction thus preventing the tape from being inadvertently fed backwardly into the machine.

105 110 115 120 125 A tape guide member 49 is detachably secured to the side frame 11 by one of the screws 12. This guide member is arranged in front of the roller 42, and is provided with a cutting edge 50, for the purpose of cutting the tape after the desired length passes from the machine. A spring device or guide 52 co-acts with the tape as it passes from the feed roller to the discharge opening in the machine and guides the tape over 130

and presses it with the adhesive side thereof down in contact with a moistening felt or pad 53. The member 52 is secured to the rear of the member 49 above the roller 42, 5 and bears at its forward free end portion against the tape.

The moistening pad 53 is preferably formed from a block of felt substantially U-shaped in cross section and serrated on its 10 upper contact face, as indicated at 55, to spread the moisture evenly and effectively over the entire gummed surface or side of the tape, as the latter passes from the machine. The moistening pad is contained in a 15 removable tank or container 54, mounted in the machine and adapted to slide into and out of place on inwardly projecting L-shaped flanges 54^a formed on the side frames 10 and 11, as best shown in Figs. 2 and 4. 20 Recesses 56 are provided in the side frames where the tank 54 slides into position. Studs 57 are formed on the slightly resilient sides of the metal tank and when the latter slides into position these studs spring into 25 the registering recesses 56, to hold the tank against accidental displacement from the machine.

It will be observed that by removing the cap 22, and raising and inking the printing 30 rollers to the dotted line position indicated in Fig. 5, the tape can be readily threaded around the platen or impression roller 23. By drawing the handle 28 slightly to the rear from the dotted line position in Fig. 5, 35 the handle will be released from locking engagement with the part 51 of the frame. The pivots 27 of the printing roller will at the same time be displaced from the supporting portions 32 of the bearing slots 25, and 40 will move into the vertically disposed portions thereof, when the printing surface of the wheel 25 will be forced into contact with the ungummed surface of the tape 13 where it surrounds the platen 23, the weight of inking rollers bearing on the printing roller and forcing it down to and maintaining it at the printing position, as shown in Fig. 2. The tape is then fed under the guide roller 37, 45 up over the roll of tape 15, and from the latter between the feed roller and its companion pressure roller 45, where it is gripped between said last mentioned rollers and automatically fed over the serrated moistening surface 55 of the pad and under cutting 50 edge 50, as the tape passes from the machine.

It will be understood therefore that by turning the finger wheel 44 the rollers 42 and 45 will be rotated drawing the tape, which 60 is intermediate said rollers and engaged thereby, forward. The tape as it is thus fed forward is drawn from the roll 15, under and around the platen or impression roller 23, and between the latter and the surface of 65 the printing roller, thence around the guide

roller 37, and over the surface of the roll 15. The tape is then fed forward over the moistening surface 55 of the pad, the adhesive side of the tape being held in contact therewith by the spring guide 52. When a sufficient length of tape has been fed forwardly it may be cut off with the aid of the knife 50, by moving the tape up against the cutting edge of the knife. Thus there will be no waste of tape and no handling of it. 70 There is no necessity whatever for the user of the machine to handle the sticky end tape to draw the tape forward through the machine as this may be effected at any time with the aid of the finger wheel 44. 80

From the foregoing description it will be seen that side frames 10 and 11 provide a substantial support at opposite ends of the shafts of the various rollers, such as the impression roller or platen 23, the supporting 85 spindle 16 of tape roll etc. It will likewise be seen that the various working parts and the tape itself are effectively protected and housed, but that, nevertheless, access may be readily had to various parts of the device 90 and to the tape when desired; that the machine is simple in construction and compact; that the parts may be readily assembled, detached or replaced if desired; that the parts are strong and reliable in use and cannot be 95 readily deranged or broken; and that the machine as a whole is efficient in use and inexpensive to manufacture.

Furthermore, it will be seen that the position of printing roller at the lower rear portion of the machine, near the open end of the frame, facilitates the ready removal of the printing roller when desired, and that simple and efficient means are provided for locking 100 the printing roller in the non-printing position, and for removing the weight of said printing roller and the inking rollers from the tape. It will be understood, moreover, that the construction is such that the tape on the roll 15, and at all points in its passage through the machine, is accurately guided or directed at both side edges, and is accurately controlled and properly directed under tension over the various rolls and devices which co-act therewith so that there is 105 no opportunity for the tape to twist or skew in its passage through the machine.

While I have described with considerable detail one form of my invention it should be understood that various changes may be made without departing from the scope of my invention and that various parts of the machine may be used without others.

What I claim and desire to secure by Letters Patent is:

1. In a machine of the character specified, the combination of means for supporting a roll of gummed tape and guiding it through the machine, and printing means for automatically effecting an imprint on the tape 110 115 120 125 130

- as it is fed through the machine, said printing means comprising a printing roller, weighted means which cause said printing roller to bear against the ungummed surface 5 of the tape thus effecting an imprint thereon and turning movement of the printing roller through its contact with the tape, hand actuated releasing means operable at will for moving the printing roller away from 10 the tape and against the action of the weighted means for said roller, and locking means adapted to lock said release means in its releasing position and to maintain the printing roller indefinitely in the released 15 or non-printing position.
2. In a machine of the character specified, the combination of means for supporting a roll of gummed tape and guiding it through the machine, and printing means for automatically effecting an imprint on the tape as 20 it is fed through the machine, said printing means comprising a printing roller mounted to press by its own weight against the ungummed face of the tape, a plurality of 25 weighted inking rollers adapted to bear one against another and one of them bearing against the face of the printing roller, the inking rollers being mounted so that the weight thereof is exerted against the printing roller to force the latter into contact with the tape and thus effect an imprint on the tape as it is fed through the machine, and hand actuated means operable at will for lifting said printing and inking rollers 30 against their weight and for holding the printing roller off the tape in a non-printing 35 position.
3. In a machine of the character specified, the combination of means for supporting a 40 roll of gummed tape and guiding it through the machine, and printing means for automatically effecting an imprint on the tape as it is fed through the machine, said printing means comprising a printing roller, a shaft 45 for said printing roller, open mouth bearing in the frame of the machine and in which the ends of said shaft may be received, and a handle provided with bearings in which said shaft is likewise received and by means 50 of which handle the printing roller may be readily introduced into, shifted along or removed from its bearing in the frame.
4. In a machine of the character specified, the combination of means for supporting a 55 roll of gummed tape and guiding it through the machine, and printing means for automatically effecting an imprint on the tape as it is fed through the machine, said printing means comprising a printing roller, a shaft for said printing roller, open mouth bearing

in the frame of the machine and in which the ends of said shaft may be received, and a handle provided with bearings in which said shaft is likewise received and by means of which handle the printing roller may be 65 readily introduced into, shifted along, or removed from its bearings in the frame, the construction of said handle being such that it may be readily detached from the printing roller when desired. 70

5. A tape machine comprising a main frame partly closed and including two side frames, one of the said frames having a slot therein for the threading of the tape terminating in an enlarged bearing, and the 75 other of said frames having a restricted bearing in line with the bearing in the first named side frame, a shaft mounted in the restricted bearing and having removably mounted thereon a cap, seated within the enlarged bearing, an impression roller removably mounted on the said shaft, and a tape-holding shaft. 80

6. A tape machine comprising a main frame including two side frames, a tape 85 holding shaft, a contact device adapted to bear on the roll of tape, a removable impression roller mounted in said frame, a grooved bearing in each side frame in the rear portion thereof and extending from 90 rear forwardly and thence downwardly, a removable printing roller, and a removable adjusting handle on said printing roller, the shaft of said roller projecting through sides of said handle and sliding into said 95 grooved bearings in said frame and carrying said printing roller to printing position by gravity. 95

7. A tape machine comprising a main frame including two side frames, a tape 100 holding shaft, a removable impression roller or platen, a removable printing roller, a raising and lowering handle on said printing roller, grooved bearings on inside of each side frame and on which the shaft of 105 the printing roller is supported when printing is not desired, two weighted inking rollers removably resting on said printing roller, and grooved bearings in said side frame to guide the shafts of said inking 110 rollers. 110

Signed at the borough of Manhattan, city of New York, in the county of New York, and State of New York this 13th day of Feb., A. D. 1915.
